UNITED STATES PATENT OFFICE.

ALFRED J. KINNUCAN, OF DETROIT, MICHIGAN, ASSIGNOR TO BRISCOE MANUFACTURING COMPANY, OF DETROIT, MICHIGAN, A CORPORATION OF MICHIGAN.

STEERING-WHEEL FOR AUTOMOBILES.

No. 909,807.

Specification of Letters Patent.

Patented Jan. 12, 1909.

Application filed May 22, 1907. Serial No. 375,472.

To all whom it may concern:

Be it known that I, ALFRED J. KINNUCAN, who am a citizen of the United States, residing at Detroit, county of Wayne, State of Michigan, have invented a certain new and useful Improvement in Steering-Wheels for Automobiles, and declare the following to be a full, clear, and exact description of the same, such as will enable others skilled in the art to which it pertains to make and use the same, reference being had to the accompanying drawings, which form a part of this specification.

My invention relates to steering wheels for automobiles, and has for its object an improved device of the type named, which is of greater strength than the cast brass ones now used, and which is of much less weight, and can be produced much more cheaply.

It also relates to arrangements for carrying up through the metal or web portion of the steering wheel the connections leading to various operative parts, such as the battery, throttle, etc., now commonly carried on the stem of the steering wheel beneath the wheel, and in exceedingly inconvenient position as regards its ready handling.

In the drawings:—Figure 1, is a perspective of the stud and web of the wheel, with only one arm of the metal carried out to, and bearing on its end, the small segment of the wooden portion of the wheel. Fig. 2, is a sectional elevation of the same. Fig. 3, is a plan of the same. Fig. 4, is a sectional elevation of the modified form in which the connections of the various operative parts are carried up through the head. Fig. 5, is a plan of this form.

The arms or web portion 1 of the device are preferably made of stamped steel, which possesses sufficient rigidity, and of course is much cheaper than the cast brass pieces now used. The portion of the handle 1^a shown is of the usual type.

2 is an acorn or "dome" nut, which is screwed to the threaded top 3 of the crown piece 4, which is connected directly with the steering stem.

The arms 1 are in two diametrical pieces, which intersect each other in this case at right angles, and are not only brazed and riveted together, but are further held in position with respect to one another by the

dowel pin 5, which, projecting from the top 55 of the crown piece, passes through them. I find that the combination of this rigid union at the center, crowned as it is by the tight engagement of the nut against the upper surface of the intersecting arm, in combination with the binding effect of the wooden handle 1^a, gives ample rigidity to the slightly dished web formed by the somewhat up-bent arms.

By the substitution for the dome nut 2 of 65 a plain nut 6, so that no obstacle is offered to the extent thereabove of the sleeve 7, I am enabled to carry above the web portion of the wheel the various controls, such as the throttle 8 and spark stem and lever 9, 70 which, of course, requires that the crown piece 41 be completely bored for the extent therethrough of the controls, instead of being a blind passage which does not extend through to the upper surface, as illustrated 75 in Fig. 2. These are protected by the crown piece 41, and the supplemental sleeve 10, from being twisted out of their desired adjustment when the steering wheel is turned, and at the same time make it possible to 80 control these various operative parts without removing the hand from the steering wheel to the comparatively inconvenient position therebeneath.

It is of course obvious that the number 85 and position of both the dowel pins 5 and rivets 12 can be varied as desired.

What I claim is:—

In combination with a steering post, a plurality of originally independent intersecting arms supported thereby, means whereby said arms are held thereto and in desired relative position with respect to one another, a crowning nut adapted to be screwed to the top of the post and, by pressure against the 90 adjacent portions of the arms, to supplement the action of said holding means, and an encircling rim piece engaging the end portions of each arm whereby the entire wheel portion is correlated, substantially as described.

In testimony whereof, I sign this specification in the presence of two witnesses.

ALFRED J. KINNUCAN.
